[57] **ABSTRACT**

A continuous forms press converts a roll of envelope paper into a continuous envelope form having a pair of longitudinal score lines spaced inwardly from the sides of the strip to provide side margins, a longitudinal row of pin feed holes in each of the side margins, a plurality of successive integral envelope blank sec-

tions, a first transverse line of weakness on each of the envelope blank sections constituting a first fold line between a bottom sheet portion and a top sheet portion, a second transverse line of weakness on each of the envelope blank sections constituting a second fold line between the top sheet portion and a closure flap portion, and adhesive coatings on the closure flap and on the top sheet portion adjacent the side margins. Indicia are imprinted on each of the envelope blank sections signifying the relative position of the pinfeed holes with the leading edge of the envelope blank section. The continuous envelope form is fan folded along the first fold line of each envelope blank section to form a zig-zag folded stack suitable for feeding into a computer print-out device or an automatic typewriter where the envelope blank sections are automatically addressed in succession with addresses contained in a tape or punch card memory. The continuous form is again fan folded along the first fold line into a zig-zag stack and fed into a continuous forms envelope converter in which the continuous form is separated into separate envelop blanks and simultaneously portions of the side margins are died out, leaving side flaps integral with the bottom sheet portion. The converter folds over the side flaps, folds a top sheet portion of each blank over a bottom sheet portion thereof along the first fold line, activates the adhesive coatings adjacent the side margins of the top sheet portion for securing the side flaps thereto, and folds the closure flap portion over the bottom sheet portions. In order to facilitate proper alignment of a continuous envelope form with the feed pins of the envelope converter, index indicia corresponding to the indicia on the envelope blank section and a fold line index mark are provided on the converter. In addition, blocking means are provided for diverting a leading partial envelope blank section after it is separated from the strip. The converter is adjustable to accommodate continuous forms of different widths to provide envelopes of different lengths.

**CONTINUOUS FORMS ENVELOPE CONVERTER
SYSTEM**

BACKGROUND OF THE INVENTION

This invention relates to envelope making apparatus and a method for making envelopes and, more particularly, to a system for converting a roll of envelope paper into a continuous form which is automatically addressed and which is thereafter converted into standard envelopes.

It is frequently necessary to mail envelopes stuffed with form letters, advertising material, circulars, or the like to a large number of addresses. Since the addressing of the envelopes manually from a mailing list is very time consuming, it has become the practice to employ automatic business machines within the memory of which the mailing list is stored for automatically preparing addressing labels for application to the envelopes. However, this practice requires that the labels be secured to the envelopes in an additional operation. It has also been suggested that addressing machines be employed having pre-addressed plates which may be employed for printing in sequence directly upon the envelopes, but systems of this character require a great deal of storage space for the addressing plates and require special machinery for making the plates.

It is therefore desirable to provide a system in which envelopes may be addressed directly from automatic computerized printers or typewriters which are programmed to print out addresses from a computer memory, and there have been a number of suggestions for addressing envelopes in this way. For example, it has been proposed that previously formed envelopes be adhesively secured to a continuous carrier strip of "computer" paper having rolls of pinfeed holes adjacent its side margins so that it might be easily fed through automatic computerized printing equipment. However, this system requires that the envelopes be secured to and detached from the carrier strip which is then discarded. It has also been suggested that addresses be printed directly upon a continuous form which is provided with pinfeed holes to facilitate pin feeding into automatic printing equipment and which is converted into envelopes by laminating it to a second continuous strip. The resulting envelopes are unconventional, different from the style of envelope customarily used in business practice, and are not adaptable for subsequent automatic stuffing and sealing operations.

The foregoing drawbacks of prior art equipment were overcome in the envelope converter system disclosed in my prior application, Ser. No. 751,467, filed Aug. 9, 1968, now U.S. Pat. No. 3,552,282, for "Continuous Forms Envelope Converter System." This prior application discloses a system for converting a continuous strip of paper into separate addressed envelopes. The system includes press means for providing perforated lines on the strip transversely of the strip to divide the strip into a plurality of envelope blanks, a pair of score lines transversely of each blank to provide a first main fold line between a bottom sheet and a top sheet and a second fold line between the top sheet and a closure flap, a pair of longitudinal lines spaced inwardly from the sides of the strip to provide side margins, the longitudinal lines being score lines adjacent the bottom sheets to provide side flaps integral with the bottom sheets and perforated lines adjacent the top

sheets to provide side trim zones, and a row of pinfeed holes within each of the side margins. The press includes adhesive coater means for providing adhesive coatings on the closure flap and adjacent to the side margins of the top sheet. The strip is folded into a continuous zig-zag folded stack suitable for feeding into automatic computerized printing equipment, the folds being effected along the perforated lines corresponding to the leading edge of each envelope blank. After the strip is pre-addressed in the automatic printing equipment, it is again folded into a zig-zag folded stack along the same fold lines and fed into a continuous forms envelope converter. This converter includes means for intermittently feeding the strip to bring the transverse perforated lines beneath a cutter knife which is synchronized with the intermittent feed to separate the strip into envelope blanks. The blanks are then conveyed past side trimmers in the form of rollers engaging the side margins, which remove the side trim zones by separating them along the longitudinal perforated line leaving side flaps integral with the bottom sheet. The blanks are conveyed past side flap folders positioned in the path of the side flaps for folding the side flaps over the bottom sheet. The envelope blanks are then fed into means for folding the top sheet over the bottom sheet and are conveyed past heaters which activate the adhesive coatings on the top sheet to seal the side flaps to the top sheet.

Although the system disclosed in my prior application has fulfilled the objective of producing automatically pre-addressed envelopes of conventional format, it has been found that this system is subject to a number of limitations in practice. For example, the envelope converter apparatus of my prior application is designed to receive a continuous envelope form having a fixed predetermined width and to produce envelopes having a fixed predetermined length only. If envelopes of a different length are desired. Or if the continuous envelope form is provided in a different width due to the requirements of the automated address printing equipment, it is necessary to provide a separate machine engineered to accept forms of the new width. The envelope converter of my prior application produces envelopes with the closure flap open. It has been found, however, that it is more advantageous to provide the envelopes with the closure flaps folded closed. Conventional automatic inserting equipment ordinarily require the envelopes be provided with the closure flaps folded closed and are provided with means to open the envelopes prior to inserting. When the closure flaps are closed, the flap glue is not exposed to the atmosphere, avoiding curling of the envelopes which would cause difficulties in the inserters. Because the flap is not exposed, it is protected from tearing and mutilation.

The system as disclosed in my prior application employs a continuous envelope form in which transverse perforated lines are employed at the ends of each envelope blank of the strip, and the form is folded along these perforated lines to form a zig-zag folded stack. A vertically reciprocating cutter knife is provided for separating the envelope blanks from the strip, and it is necessary that the knife engage the strip accurately along these transverse perforated lines.

The side trim removal rollers of my prior application are positioned at a point following the cutter knife and

are effective after the blanks are separated from the strip. These rollers strip off the side trim by pulling it free along the longitudinal perforated lines. However, it has been found in practice that the side trim is not uniformly separated from the blanks. When the blanks are guided into the rollers, one side trim frequently breaks off before the other, causing the blank to enter the side folders with a crooked orientation. In addition, the weak perforations frequently cause separation of the side trim when the strip is being fed through the computerized printing equipment creating problems with the operation of that equipment.

The envelope converter apparatus of my prior application employs intermittent feed means for feeding the strip from the zig-zag folded stack. The feed means includes a reciprocating rack, a slip clutch, a brake, and detent means for preventing reverse movement of the pinfeed belts upon reverse reciprocation of the rack. However, slippage in this intermittent drive system has caused timing errors which were avoided only by the adoption of a complex electrical system (not shown in my prior application).

SUMMARY OF THE INVENTION

It is accordingly the principal object of the invention to provide an improved system for automatically addressing and forming envelopes for large scale mailings.

It is also an object of the invention to provide an improved envelope addressing system which provides addressed envelopes quickly and inexpensively, which eliminates costly addressing equipment, and which is substantially fully automated.

More specifically, it is an object of the invention to provide an improved envelope forming system which makes use of an improved continuous envelope form adapted to be fed through automatic computerized printing equipment to be pre-addressed therein and which converts the continuous form into envelopes of standard format.

Another object of the invention is the provision of an improved continuous envelope form specially prepared for feeding through automatic computerized printing equipment and for conversion into envelopes of standard format.

An additional object of the invention is the provision of an improved continuous forms envelope converter for converting a continuous envelope form, which has been pre-addressed in computerized printing equipment, into standard pre-addressed envelopes.

It is a further object of the invention to provide an improved continuous form envelope converter for converting a continuous envelope form of the aforementioned character into envelopes by separating it into individual envelope blank sections, dieing out excess material from the side margins thereof, folding side flaps, folding the blank about a main fold line, sealing the side flaps, and folding over a closure flap.

An additional object involves the provision of an envelope converter of the aforementioned character which is adjustable to receive continuous envelope forms of different widths and for producing completed envelopes of different lengths.

Yet another object involves the provision of an improved envelope converter having improved means for folding the closure flap.

Still another object is directed to the provision of an improved continuous envelope form having a plurality of integral envelope blank sections and characterized by the absence of a perforated line at the boundary between adjacent envelope blank sections. A related object is the provision of an improved envelope converter which includes knife means for separating the envelope blank sections at their trailing edge.

10 A further object of the invention relates to the provision of improved means for separating side trim from a continuous envelope form. More specifically, it is an object of the invention to provide die means operating simultaneously with the knife means for dieing out portions of the side margins of the continuous envelope form leaving side flaps integral with bottom sheet portions thereof. A related object is the provision of means for deflecting the side trim to a waste receptacle.

Another object relates to the provision of an improved cam drive for the knife head which vertically reciprocates to separate the continuous envelope form into separate envelope blank sections.

Still another object pertains to the provision of an envelope converter with improved intermittent feed means.

In order to accommodate conventional computerized print-out equipment it is necessary to space the pinfeed holes of the continuous envelope form at a spacing which is standard for such equipment. However, due to the standard height of business envelopes, it is not possible to position the pinfeed holes of each envelope blank section of the continuous envelope form the same distance from the leading edge of the section. It is accordingly necessary to adjust for this different spacing; otherwise, envelope blank sections will be engaged by the knife means at different positions, thereby resulting in envelopes having different dimensions. It is accordingly an object of the invention to provide indicia means for facilitating the feeding of a continuous envelope form into the continuous envelope converter in a manner accurately positioning the leading edge of each blank section with respect to the knife means.

Due to the fact that the continuous envelope form of the present invention is fan folded along the first fold line between the top sheet portion and the bottom sheet portion of each envelope blank section, the leading envelope blank section of each zig-zag folded stack is a partial envelope blank section. Since this partial section cannot be converted into an envelope by the envelope converter of the present invention, it is necessary to dispose of it. Accordingly, it is an object of the invention to provide means for diverting the leading partial envelope blank section to a waste receptacle after it is separated from the continuous envelope form.

Briefly, the invention contemplates a system and method for converting a continuous strip of paper into separate addressed envelopes. The system includes 60 press means for providing the continuous strip with a pair of longitudinal score lines spaced inwardly from the sides of the strip to provide side margins, a longitudinal row of pinfeed holes in each of the side margins, a plurality of successive integral envelope blank sections, a first transverse line of weakness on each of the envelope blank sections constituting a first fold line between a bottom sheet portion and a top sheet por-

tion, a second transverse line of weakness on each of the envelope blank sections constituting a second fold line between the top sheet portion and closure flap portion, the closure flap portion having an edge corresponding to the leading edge of the envelope blank section contiguous with the trailing edge of an adjacent envelope blank section, and adhesive coatings on one side of the strip on the closure flap portion and on the top sheet portion adjacent the side margins. The press means also provides indicia on successive envelope blank sections signifying the relative position of the pinfeed holes thereon with respect to the leading edge thereof. The strip is fan folded along the first fold line to form a zig-zag folded stack which is received in printer means for successively printing addresses on one of the top and bottom sheet portions of successive envelope blank sections and for refolding the continuous strip along the first fold line as an addressed zig-zag folded stack. A continuous forms envelope converter according to the invention includes a pair of intermittent feed means for engaging respectively the rows of pinfeed holes in each side margin of the continuous envelope form for feeding the form from the zig-zag folded stack. The intermittent feed means includes a partial gear having teeth only part way therearound and provided with a cam cooperating with a cam follower on an intermitting gear driven by the partial gear to prevent teeth clash. The converter includes knife means for separating the envelope blank sections from the strip at the trailing edge of each envelope blank section, and a pair of side die means for dieing out the portions of the side margins adjacent the top sheet portion and the closure flap portion, leaving side flaps integral with the bottom sheet portion. The die means is driven to operate simultaneously with the knife means separating the blank sections from the strip. As the knife means separates the blank from the strip, drive rollers become effective to convey the blank to a pair of side flap fold means for folding the respective side flaps over the bottom sheet portion and into engagement with adhesive coatings adjacent the side margins of the top sheet portion. Means are provided for folding the top sheet portion over the bottom sheet portion along the first fold line and directing the blank along a downward path past heater means for activating the adhesive coatings on the top sheet portion for securing the side flaps thereto. The blanks are received by means for folding the closure flap portion over the bottom sheet portion.

In order to facilitate adjustment of the envelope converter for receiving continuous envelope forms of different predetermined widths and for producing completed envelopes of different predetermined lengths, the converter includes lateral adjustment means for adjusting the spacing between the pair of intermittent feeding means, the pair of die means, the pair of side flap fold means, and the pair of heater means. It is contemplated by the invention that the adjustment means include first means for simultaneously adjusting the spacing between the pair of intermittent feed means and the pair of die means and second means for simultaneously adjusting the spacing between the pair of side flap fold means and the pair of heater means.

In order to divert the leading partial envelope blank section of the continuous envelope form to a waste receptacle, it is contemplated by the invention that the leading edge of the strip be fed into the envelope converter while the intermittent feed means, knife means, and side die means are hand driven toward a blocking structure which is placed in position to block the passage of the leading partial envelope blank section and direct it to the waste receptacle. This blocking structure is then returned to a position no longer blocking passage of the full envelope blank sections to the side flap fold means. The invention also contemplates a method of inserting the leading end of the continuous envelope form into the envelope converter by adjusting the position of a feed pin into alignment with an index indicia on the converter corresponding to indicia on the envelope blank sections signifying the spacing of the pinfeed holes on the respective envelope blank section from the leading edge thereof and engaging the first full envelope blank section with the feed pins of the intermittent feed means with the first fold line of the leading full envelope blank section in alignment with an index mark on the envelope converter. The index indicia and the index mark are so positioned that the leading edge of the first full envelope blank section will then be properly positioned beneath the knife means.

The foregoing and other objects, advantages, and features of the invention and the manner in which the same are accomplished will become more readily apparent upon consideration of the following detailed description of the invention when taken in conjunction with the accompanying drawings, which illustrate preferred and exemplary embodiments.

BRIEF DESCRIPTION OF THE DRAWINGS

FIG. 1 is a schematic diagram of a continuous forms envelope converter system of the invention;

FIG. 2 is a partial plan view of a continuous envelope form used in the system of the invention;

FIG. 3 is a perspective view of a completed envelope of the invention;

FIG. 3A is a partial sectional view along line 3A—3A of FIG. 3;

FIG. 4 is a plan view of a continuous envelope forms converter of the invention with parts broken away;

FIG. 16 is a sectional view along line 16—16 of FIG. 14;

FIG. 17 is a schematic section view along lines 17—17 of FIG. 5 with parts broken away; and

FIG. 18 is a partial schematic perspective view of the converter apparatus of FIG. 4.

DETAILED DESCRIPTION OF THE DRAWINGS

Referring to FIG. 1, it will be seen that a continuous forms envelope converter system of the invention includes a rotary forms press 20 which converts a strip 22 of envelope paper stock from a roll 24 into a continuous envelope form 26, shown in more detail in FIG. 2, fan folded into a continuous zig-zag folded stack 28. Since rotary forms press 20 comprises conventional apparatus, it will not be described in detail herein. However, it is to be understood that this press applies score lines to the strip 22, punches a pair of rows of pinfeed holes therein along each of the edges, cuts perforations and diagonal cuts therein, applies adhesive coatings thereto, and prints printed matter thereon. Turning to FIG. 2, it will be seen that the continuous envelope form 26 includes a pair of longitudinal lines of weakness or score lines 30 and 32 spaced a short distance inwardly from the respective side edges 34 and 36 of form 26 to define a pair of side margins 38 and 40. A longitudinal row of pinfeed holes 42 is provided in side margin 38, while a similar longitudinal row of pinfeed holes 44 is provided in side margin 40. The continuous envelope form 26 is provided with a plurality of successive full envelope blank sections 46 each of which is provided with a transverse line of weakness of perforated line 48 extending from side edge to side edge of the strip and constituting a first fold line between a bottom sheet portion 50 and a top sheet portion 52 of full envelope blank section 46. Each full envelope blank section is also provided with a transverse line of weakness or perforated line 54 extending between score line 30 and score line 32 and constituting a second fold line between the top sheet portion 52 and a closure flap portion 56. The leading edge of closure flap portions 56 corresponds to the leading edge of each envelope blank section 46 and is contiguous with the trailing edge of the next leading envelope blank section. While the leading and trailing edges of the envelope blank sections are not marked, a line of division 58 between successive envelope blank sections is shown in FIG. 2 and will, as will be explained more fully hereinafter, be the line along which each envelope blank section is separated along its trailing edge from the continuous envelope form. It will be observed that the line of division 58 does not extend perpendicularly from the side edges but extends slightly forwardly of the line of perpendicularity so that the closure flap portion will have a point 60 representing the apex of a quarter inch throat to facilitate engagement with automatic inserter machinery. The side edges of the closure flap portions

56 are defined by a pair of diagonal slashes 62 and 64 extending inwardly from the points of intersection between second fold line 54 and longitudinal score lines 30 and 32, respectively, and the line of division 58.

As will be explained more fully hereinafter, side trim zones 66 and 68 will be separated from the envelope blank sections 46. Each of these side trim zones will incorporate portions of the side margins 38 and 40, respectively, extending from the first fold line 48 to the line of division 58 and incorporating the portion of the form between diagonal slashes 62 and 64 and side edges 34 and 36, respectively.

15 After side trim zones 66 and 68 are removed, the portions of the side margins contiguous with bottom sheet portion 50 will remain. These portions will serve as side flaps 67 and 69 respectively of the completed envelope. In the continuous envelope form 26 as seen in FIG. 2, the top or printed side of the form is visible and various printing material, such as return addresses and advertising matter (not shown), may be printed thereon as desired. In addition, indicia 70, 72 and 74 are printed on successive envelope blank sections and will have the purpose of facilitating proper insertion of the continuous envelope form into envelope converter apparatus, as will be described in more detail hereinafter.

30 As seen in phantom line in FIG. 2, adhesive coatings 30 are provided on the opposite side of form 26. A first adhesive coating 76 is provided on the closure flap portions 56 adjacent the leading edge thereof, and a pair of adhesive coatings 78 and 80 are provided on the top sheet portions 52 adjacent the longitudinal score lines 30 and 32, respectively. These adhesive coatings are of a type which is heat activatable so that when the envelope form is subjected to heat and pressure, as will be explained more fully below, the adhesive coatings will become activated.

35 40 As will be noted from FIG. 2, the envelope blank section 82 between the leading line of division 58 and the leading end 84 of form 26 is much shorter than full envelope blank sections 46 constituting the remainder of form 26. In point of fact, the distance between leading end 84 and the leading line of division 58 is equal to the distance between the first fold line and trailing edge of each of the full envelope blank sections 46. For this reason, envelope blank section 82 will be referred to hereinafter as a partial envelope blank section.

45 Since it is intended that the continuous envelope form 46 will be fed through automatic computerized addressing equipment, it is desirable that the pinfeed holes of the two longitudinal rows of pinfeed holes be spaced in accordance with the standards of conventional computer print-out paper. To this end, the pinfeed holes in each row are spaced one-half inch apart, center-to-center. This would appear to require that the length of each envelope blank section be such that the pinfeed holes are at the same relative distance from the leading edge thereof on each envelope blank section, but this would result in envelopes having an unconventional dimension, heightwise. This difficulty is avoided, however, in accordance with the present invention, by orivudubg the envelope blank sections in recurrent series of n envelope blank sections each of which has a different relative position of pinfeed hole to leading

edge. The total length of the recurrent series is selected so that this relative position of pinfeed hole to leading edge will repeat every n envelope blank sections. Thus, in one example adopted in a practical embodiment of the invention, the recurrent series includes three envelope blank sections. This enables the use of envelope blank sections having a total length longitudinally of the form of $9\frac{1}{2}$ inches with the total length of the recurrent series of three envelope blank sections being 28 inches. Since a $\frac{1}{2}$ inch spacing is adopted for the pinfeed holes, it will be readily apparent that the relative position of pinfeed holes to leading edge will repeat every three envelope blank sections and will be the same on each envelope blank section of a recurrent series as on the corresponding envelope blank section in the other series on the form.

Each of the indicia 70, 72 and 74, which, in the example given, are the letters G, R, and B, signify which of the relative positions a particular envelope blank section embodies. That is, the relative spacing of pinfeed holes on envelope blank sections marked by indicia G will be the same as the relative position on all other envelope blank sections marked G; the relative position of pinfeed holes to leading edge on all envelope blank sections marked R will be the same; and, likewise, the relative position of pinfeed hole to leading edge on all envelope blank sections marked B will be identical. As will be explained in more detail hereinafter, this information will be used when an envelope form 26 is fed into envelope converter apparatus to ensure that the envelope blank sections are separated at the proper line of division.

In order to provide envelope blank sections in the aforementioned recurrent series, rotary forms press 20 may include a printing cylinder with a 28 inch circumference which will provide an entire series of three envelope blank sections. The rotary forms press will also include a pinfeed hole punching ring which has a circumference of 22 inches providing a pinfeed hole every one-half inch along the continuous form.

As mentioned above, the lines of division 58 corresponding to the trailing edge of each envelope blank section do not constitute fold lines. Accordingly, zig-zag folded stack 28 is not formed by folding the continuous strip 26 along a fold line corresponding to an end of the envelope blank section as was the case in my prior application, Ser. No. 751,467. In accordance with the present invention, the continuous form 26 is fan folded along the first fold lines 48 of each of the envelope blank sections. After the form is thus folded into a zig-zag folded stack, it is transported to a computerized address printer 100. The printer will be a print-out device of conventional computer equipment or a pin-fed automatic typewriter, which includes a memory in the form of pre-punched cards or magnetic tape containing address information, and which is programmed automatically to print the addresses stored in the memory on successive envelope blank sections 46 on either the top or bottom sheet portion thereof. Such equipment is readily adapted for quick and inexpensive correction or updating of the mailing list. After continuous form 26 is thus addressed, it is refolded into a zig-zag folded stack 28 along first fold lines 48. The continuous form will now comprise a plurality of envelope blank sections 46 each of which is pre-ad-

dressed with a particular address as determined by the computer or automatic address printer 100.

The continuous envelope form 26 will now be in condition for conversion into individual pre-addressed envelopes. This is accomplished in the continuous forms envelope converter 110. As shown in FIG. 1, envelope converter 110 is of such size that it may be conveniently positioned upon a table 112. The addressed zig-zag folded stack 28 may be positioned at one end of table 112 so that continuous form 26 may be readily fed into envelope converter 110. As will be described in greater detail hereinafter, envelope converter 110 will separate the envelope blank sections 46 from continuous envelope form 26 and convert them into completed envelopes 114 which are delivered from converter 110 to conveyor belt 116. After a supply of completed addressed envelopes 114 have accumulated in a stack 118, the stack may be transported to automatic inserting equipment which will serve to stuff the envelopes with the material to be mailed and which will subsequently seal the closure flaps of the envelopes for mailing.

Considering the continuous forms envelope converter 110 in greater detail and referring initially to FIGS. 4, 4A, 5 and 7, it will be observed that continuous form 26 is fed into envelope converter 110 by means of a pair of intermittent pinfeed means 120 only one of which is shown in FIG. 4. As seen in FIG. 4A, however, identical pinfeed means 120 are provided on both sides of the converter. With particular reference to FIGS. 5 and 7, it will be seen that each of the pinfeed means is in the form of a continuous tractor belt 122 having a plurality of feed pins 124 projecting therefrom. The feed pins are spaced apart with the same spacing as the pinfeed holes 42 and 44 of continuous envelope form 26; thus, in the example given above, the spacing will be one-half inch, center-to-center. As will be explained in greater detail hereinafter, pinfeed holes 42 and 44 of continuous form 26 are engaged with the respective pinfeed means 120, which are driven in an intermittent fashion to advance form 26 to feed each envelope blank section successively into converter 110. After so advancing the form, intermittent feed means enters a dwell period to permit separation of the envelope blank sections from the continuous envelope form 26, as will be explained hereinafter.

With reference to FIGS. 4, 5, 6, 9, 10, 11 and 12, the drive means for pinfeed means 120 will now be described. A motor 126 drives an overrunning clutch pulley 128 which is coupled by a drive belt 130 to a compound pulley 132 on a shaft 135. A timing belt drive pulley 134 on shaft 135 drives a timing belt 136 to drive a timing belt pulley 138 (FIG. 5) mounted on a shaft 140. A special partial gear 142 is mounted on shaft 140. As will be seen most clearly from FIGS. 9, 10, 11 and 12, gear 142 is provided with forty gear teeth 144 over one-half of its periphery. Gear 142 is made from an eighty tooth gear, one-half of the teeth of which are milled off to form a smooth portion 146 extending about the other half thereof. Gear 142 is adapted to become engaged with an intermitting driven gear 148 having 40 teeth completely around its periphery. The manner in which gear 142 drives gear 148 in an intermittent fashion will be best understood

by considering FIGS. 9, 10, 11 and 12 in sequence. As shown in FIG. 9, gear 142 has its teeth 144 engaged with the teeth of gear 148. It will be observed that a cam track 150 is mounted on gear 142 for rotation therewith. A McGill cam follower 152 is mounted for rotation with gear 148 and is engageable with cam track 150. With the teeth engaged, as in FIG. 9, and with gear 142 rotating in a clockwise direction as seen in the drawing, gear 148 will be driven in a counter-clockwise direction. When the position as shown in FIG. 10 is reached cam follower 152 will engage with a lead-in track portion 154 of cam track 150 causing the teeth of gear 148 to be lifted out of engagement with the teeth 144 of gear 142, this being made possible by play in the bearings for shaft 156 upon which gear 148 is mounted. By virtue of the lead-in track the teeth of gear 148 disengage from the teeth of gear 142 without gear clash. Gear 142 will continue to rotate in the clockwise direction. However, since gear 148 is now disengaged from teeth 144, it will dwell during 180 degrees of rotation of gear 142, and be locked in this position by virtue of engagement of cam follower 152 in cam track 150. As shown in FIG. 11, the gear 142 continues to rotate and cam follower 152 has now traversed to the opposite end of cam track 150. This end of cam track 150 is provided with a lead-out track 158 serving to engage the teeth of gear 148 with teeth 144 of gear 142 without gear clash as illustrated in FIG. 12. Gear 148 will now be engaged with teeth 144 of gear 142 for 180° of rotation of gear 142. By virtue of the equality in the number of teeth on gears 148 and 142, gear 148 will be driven through a full 360° of rotation during this 180 degrees of rotation of gear 142. When, however, the gear teeth are disengaged and cam follower 152 is engaged with cam track 150, gear 148 will dwell in a non-rotational mode during the next 180° of rotation of gear 142.

Referring to FIG. 5, it will be seen that gear 148 is, in turn, engaged with a gear 160 having 24 teeth. Gear 160 is mounted for rotation with a shaft 162 upon which is also mounted a timing pulley 164. Pulley 164 drives a timing belt 166 which is engaged with a timing pulley 168 driving a shaft 170 upon which is mounted the drive wheels 172 for the pinfeed tractor assemblies 120. It will be observed that shaft 170 is square in cross-section and that wheels 172 are keyed to slide thereon in a manner to be described more fully hereinafter. The pinfeed tractor belts 122 also extend around a pair of idler wheels 174. These wheels are mounted for rotation on shafts 176 cantilevered from respective supporting members 178 of assemblies 120. These members are also mounted for movement along shaft 170 so that, in a manner to be described hereinafter, the pinfeed assemblies 120 may be laterally adjusted relative to each other.

Continuous envelope form 26 is thus advanced by feed means 120 into converter 110 to bring line of division 58 accurately beneath separating means which will be described hereinafter. The manner in which form 26 is engaged with feed means 120 to ensure that line 58 will be so positioned will be described in more detail below. For the time being, it is sufficient to note that when the line of division has reached the aforementioned position, the intimate feed means 120 will enter a dwell period corresponding to the dwell period of

gear 148 thereby retaining continuous form 26 stationary.

The central portion of form 26 will be supported by a plate 179, and the sides will be received in a pair of side die assemblies 180 provided to die out side trim zones 66 and 68. With specific reference to FIGS. 4, 4A, 5, 13 and 17, it will be noted that side die assemblies 180 include an upper die member 182 and lower die member 183. Upper die member 182 carries a die punch 184 projecting downwardly from its lower surface and positioned to be received within a die recess 185, the cutting edges of die recess 185 being formed by the edges of die elements 186 and 188 positioned on lower die element 183. The cutting edge 187 of die element 186 cooperates with punch 184 to cut along the corresponding longitudinal score line 30 or 32 between first fold line 48 and the corresponding diagonal slash 62 or 64. Cutting edge 189 of die element 188 cooperates with punch 184 to cut along first fold line 48 between side edges 34 and 36 and the corresponding longitudinal score line 30 or 32. In addition, simultaneously with the operation of the side die means, separating means to be presently described will sever continuous form 26 along line of division 58 between the envelope blank section acted upon by the side die means and the next leading envelope blank section which will thus be severed from continuous form 26 along a trailing edge corresponding to line of division 58. Upper die member 182 is vertically reciprocated along vertical guide rods 190 and 192 extending upwardly from the relatively stationary lower die member 183. This vertical reciprocation is effected by means of a timing pulley 194 driven by shaft 140 driving a timing belt 196 which, in turn, drives a timing pulley 198 on shaft 200. A pair of cams 202 are mounted on shaft 200 to engage the respective upper side die members 182. The upper side of each cam 202 is engaged by the lower surface of a bridge member 203 which is secured to the upper surface of die member 182 by bolting bridge feet 203a thereto. The lower side of each cam 202 is engaged with a roller 204 journaled on a shaft 205 in a recess 206 provided in the upper surface of die member 182. Alternatively, cam 202 may merely engage a bearing surface provided in the upper side of member 182. In either case, rotation of cam 202 will cause die member 182 to reciprocate vertically on rods 190 and 192 to bring punch 184 into die recess 185. In order to absorb the impact of die member 182, an impact foot 182a 5,13, be provided to depend from the lower surface of die member 182. As best seen in FIG. 17, this foot 182a depends from a post 182b received in a hole 182c. Post 182b has a head 182d on its upper end to abut against a shoulder provided at the bottom of a recess 182e. A spring 182f biases head 182d against this shoulder, and this spring absorbs the impact when foot 182a engages lower die member 183. It is to be noted that cam 202 is so positioned on shaft 200 that it will drive die member 182 to the lower part of its range of movement when form 26 is held stationary during the dwell period of intermittent feed means 120.

Although side trim zones 66 and 68 will now be cut free from continuous envelope form 26, in order to ensure that the side trim zones are not fed inadvertently through the remainder of the envelope converter it is desirable to provide special scrap removal means 210,

which is most clearly shown in FIGS. 4, 4A, 14, 15 and 16. It will be observed from FIGS. 4, 4A and 15 that a bracket 212 projects outwardly from upper die member 182 and that a corresponding bracket 214 projects outwardly from lower die member 183 in alignment with bracket 212. An actuating rod 216 depends downwardly from bracket 212 in alignment with a hole 218 through bracket 214. It will be observed from FIG. 15, that hole 218 intersects one side of a bore 220 extending horizontally through bracket 214. A shaft 222 is journaled for rotation in bore 220 and is provided with a flat spot 224 at a position corresponding to the intersection of hole 218 with bore 220. It will be observed from FIG. 15 that rod 216 will thus be in alignment with one side of flat spot 224. As will be evident from FIGS. 14 and 16, a bent rod 226 has a first portion 228 extending through a diametrical hole 230 through shaft 222. In addition, rod 226 has a portion 231 bent at an angle to portion 228, a portion 232 bent at an angle to portion 231, and an end portion 234 bent at an angle to portion 232. It will be observed that end portion 234 is positioned above the respective side trim zone. Shaft 222 is normally biased by a coil spring 242, having one end 244 engaged with the bottom side of rod portion 231 and another end 246 engaged with the top side of a pin 248 extending from bracket 214. Spring 242 thus serves to bias rod 226 for rotation with shaft 222 until rod portion 228 abuts against pin 248. This will be the normal position of rod 226, being illustrated in FIG. 16. When upper die member 182 descends, rod 216 will enter hole 218 and become engaged with flat spot 224 causing rotation of shaft 222 in a direction opposing the bias of spring 242. This will cause rod portion 234 to move downwardly as shown by the arrow in FIG. 16 until it engages the corresponding side trim zone 66 or 68 positively deflecting it downwardly into a waste receptacle. It is to be understood that the length of rod 216 is selected so that it engages flat spot 224 shortly after punch 184 engages the continuous envelope form. Thus, scrap removal means 210 becomes effective immediately after the side die means and separating means (to be described hereinafter) cut the side trim zones free from the form. When punch 184 is then reciprocated from recess 185, pin 216 will disengage from flat spot 224 permitting spring 242 to return bent rod 226 to the position shown in FIG. 16.

The manner in which envelope blank sections are separated along line of division 58 from continuous envelope form 26 will now be described. Referring particularly to FIGS. 5 and 6 (which is a continuation of FIG. 5), it will be seen that a timing pulley 250 mounted on shaft 140 drives a timing belt 252 which, in turn, drives a timing pulley 254 mounted on shaft 256. An eccentric 258 is mounted for rotation with shaft 256, and a crank arm 260 is driven upwardly and downwardly as eccentric 258 rotates. Crank arm 260 is pivotally engaged at 262 with a knife head assembly 264. As best seen in FIGS. 4 and 18, knife head assembly 264 extends across the full width of converter 110 between side frame members 276 and 284 and is provided with a pair of T-shaped vertical slide shoes 268 (only one of which is shown in FIG. 4) secured by means of a screw (not shown) in a groove 226 of the knife head assembly. The broad head of the vertical

slide shoe 268 is received in a vertical groove 270 provided in a vertical slide member 272. This member is attached by means of a screw 274 to side frame member 276 and by means of a screw 278 to a transverse frame member 280 which, in turn, is secured to side frame member 276 by means of the screw 282. As seen in FIG. 18, corresponding structure is provided on the opposite side secured to the other side frame member 284, these parts having been omitted from FIG. 4 to permit a clearer view of shaft 256. Thus, vertical slide shoes are provided in each of grooves 266 of knife head 264 to slide in a pair of vertical slides which are secured to side and transverse frame members.

It will be noted from FIG. 6 that knife head assembly 264 supports a cutting knife 286 which is secured to the bottom side thereof by means of a screw 288. As eccentric arm 260 moves knife head assembly down, knife 286 will engage continuous envelope form 26 along line of division 58, knife 286 being shaped as shown in phantom line in FIG. 4 to follow the shape of line of division 58. Knife 286 cooperates with a bottom knife assembly 290 extending transversely of the converter between side frame members 276 and 284. Bottom knife assembly 290 includes a fixed transverse member 292 having holes 294 receiving posts 296 depending downwardly from a lower knife abutment plate 298, this plate being normally biased upwardly by means of springs 300 in holes 294 in member 292. The sharp cutting edge of knife 286 coincides with the forward edge of knife plate 298 to ensure a reliable shearing action along line of division 58. Just in advance of knife plate 298 is a fixed plate member 302 secured by means of a screw in a recess provided in member 292. It will be understood, as previously mentioned, that knife 286 will engage knife plate 298 at the same time that punch 184 enters punch recess 185 of the side die means 180.

A normally inoperative blocking structure 304 is positioned immediately after plate 302. This blocking structure is normally in the inoperative position shown in full line in FIG. 6 so that in ordinary operation of the apparatus it will not block the progress of the continuous envelope blanks 46. It will be used, however, when a new continuous envelope form 26 is fed into converter 110 as will be explained more fully hereinafter.

When a continuous envelope form has been fed by intermittent feed means 120 to bring line of division 58 directly beneath knife 286, it will, as was previously explained, enter a dwell period so that continuous envelope form 26 will be stationary when engaged by knife 286 and by punches 184 of the side die means. It is to be understood that the leading edge of the envelope blank section 46 whose trailing edge is positioned beneath knife 286 will extend slightly in advance of a pair of drive rollers 306 which, however, will normally be ineffective to advance the envelope section. The drive rollers 306 will, however, become effective as soon as knife 286 severs the leading envelope blank section 46 from the strip. To this end, drive rollers 306 are mounted on a shaft 308 which is continuously driven in the direction of the arrow (FIG. 6) by means of a timing belt 309 driven from pulley 310 mounted on the same shaft 135 as pulleys 132 and 134. Rollers 306 cooperate with pinch rollers 312 each of which is journaled in a fork at the end of a slide rod 314 received

within a vertical slide opening 316 extending through a transverse frame member 318 extending between the side frame members, as best seen in FIG. 18. By virtue of a spring 320 acting between the top side of transverse frame member 318 and abutment 322 adjacent the top end of rod 314, rod 314 is normally biased upwardly bringing pinch roller 312 out of engagement with drive roller 306. This position of pinch roller 312 is illustrated in FIG. 6. It will be noted that a pair of brackets 324 are mounted on knife head assembly 264 extending forwardly therefrom (see FIG. 18) for vertical reciprocation therewith. A web 325 depends from each bracket 324 and is received in a corresponding slot 280a provided in transverse frame member 280 to guide the vertical movement of the bracket. The free or distal end of each of brackets 324 is provided with an adjustable abutment screw 326 which is aligned with the top end of slide rod 314. When knife head assembly 264 reciprocates downwardly, abutment screw 326 will engage the top end of slide rod 314 depressing it against the bias of spring 320 to bring pinch roller 312 in engagement with envelope blank 46 near the leading edge thereof. Screw 326 will be adjusted so that this engagement of pinch roller 312 with drive roller 306 will occur immediately after an envelope blank section 46 is severed from the strip 26. During forward movement of form 26 by intermittent feed means 120, rollers 312 will be biased out of contact with drive rollers 306 permitting the leading portion of the leading blank section 46 to pass between them. When knife head assembly 264 descends to bring knife 286 into engagement with form 26, rollers 312 will engage form 26 pressing it against rollers 306 driving the now severed envelope blank section 46 forward. It is to be noted that after engagement with form 26, knife 286 will continue to move down due to the give of plate 298 against springs 300. During the interval until knife 286 is again lifted above the normal position of plate 298 (as shown in FIG. 6), rollers 312 will be maintained in engagement with blank section 46 so that rollers 306 will continue to drive it forward, the leading portion of blank 46 being engaged by rollers 332 and 334 before rollers 312 are lifted off blank 46 as arm 260 raises knife head assembly 264. Thus, the envelope blank section 46 is positively driven through the side fold mechanism 328.

Side fold mechanism 328 is generally of the same type as that disclosed in my prior application Ser. No. 751,467 and will not be described in further detail here, reference being made to said prior application for the details thereof. It will be noted, however, that each of the pair of side fold means 328 will be positioned in the path of a respective one of side flaps 67 and 69 and will serve to lift up the side flap and then fold it over the bottom sheet portion 50 of the envelope blank section 46 in the manner described in said prior application. It is to be noted, from FIG. 6, that each of the side fold mechanisms 328 is mounted on a carriage 330 which, in a manner to be described hereinafter, will facilitate adjustment of the spacing therebetween.

As envelope blank section 46 is fed through side fold mechanism 328 it will be further driven forward by drive rollers 332 and 334 which engage respectively the bottom and top surface of the blank section. Roller 332 is mounted on a shaft 336 which is driven by a timer pulley 338 driven by a timing belt 340 engaged with a

timer pulley 342 on shaft 308 (see FIG. 4). Rollers 334 are mounted for rotation on a shaft 344 which is driven by a timer pulley 346, timer belt 350, and timer pulley 348 on shaft 352. A drive roller 354 is mounted on shaft 352 and engages the top side of the envelope blank section. A lower drive roller 356 is mounted for rotation on shaft 358 which is driven by a timer belt and pulley arrangement (not shown) from shaft 336. Shaft 352 is driven through gears (not shown) from shaft 358. Rollers 354 and 358 drive the envelope blank section into an upwardly inclined guide chute 360 providing a guide path between an upper guide plate 362 and a lower guide plate 364. A stop member 366 is adjustably positioned within the guide chute 360. When the leading edge of envelope blank section 46 engages stop 366, the first fold line 48 will be positioned over the nip between drive roller 356 and a spring loaded drive roller 370 mounted for rotation on a shaft 372 driven by means of gearing (not shown) from shaft 358. By virtue of buckling along fold line 48 due to the engagement of the leading edge with stop 366, rollers 356 and 370 will engage opposite sides of the fold line 48 and drive the envelope blank 46 along a downward path while folding bottom sheet portion 50 over top sheet portion 52. The envelope blank section will be driven past a pair of heaters 374 being engaged on their opposite sides by pressure plate 376 biased by springs 378 into engagement with the opposite side of the envelope form. As will be seen in FIG. 4A, a pair of heater means 374 are positioned to engage the envelope form at the positions where the side flaps engage the adhesive coatings 78 and 80 on top sheet portion 52. The heat and pressure provided by the heater means comprised of heater 374 and pressure plate 376, will activate adhesive coatings 78 and 80 and secure the side flaps 67 and 69 to top sheet portion 52.

After the envelope blank section 46, which now is a completed envelope 114 with its closure flap open, leaves the heater means it will be engaged on opposite sides by a pair of drive rollers 380 and 382. Drive roller 380 is mounted for rotation on shaft 384 which is driven by a timing pulley 386 on shaft 384 which, in turn, is driven by a timing belt 388 and by a timing pulley 390 on shaft 372. Roller 382 is spring-loaded and is driven by gearing (not shown) from shaft 384. Rollers 380 and 382 will drive the envelope downwardly into a second guide chute 392 which is inclined rearwardly and which is comprised of a pair of guide plates 394 and 396. The end of guide chute 392 is terminated by a stop 398 which is engaged by the folded edge of the envelope. When this occurs, second fold line 54 of the envelope will be opposite the nip between roller 380 and a spring-loaded drive roller 400, which is driven through gearing (not shown) from shaft 384. The engagement of the leading folded edge of the envelope against stop 398 will cause buckling along fold line 54, and opposite sides of fold 54 will be engaged by rollers 380 and 400 causing the closure flap portion 56 to be folded over the bottom sheet portion 50 of the envelope. The envelope will now be driven forwardly in a horizontal direction as indicated by arrow 402 to be deposited on conveyor belt 116 as shown in FIG. 1.

An important feature of the present invention is the provision of means facilitating adjustment of the con-

verter 110 to receive continuous envelope forms of different widths so as to manufacture envelopes of different lengths. This will necessitate the provision of means for adjusting the spacing between the intermittent feed means 120, the side die means 180, the side flap fold means 328, and the pair of heater means 374. It has been found to be convenient to adjust the spacing of intermittent feed means 120 and the side die means 180 by one adjustment and to adjust the spacing of the side fold means and the heater means by a second adjustment. Turning to FIG. 4 and 4A, it will be observed that lower die member 183 is tied to supporting member 178 of the intermittent feed means 120 by means of a rigid link 404, similar means being provided between the lower side die member and supporting member on each side of the machine. It will be observed, moreover, from FIGS. 5 and 13 that lower die members 183 are mounted on a pair of depending carriage members 406 and 408 which are secured to the bottom of lower die member 183 by suitable screws 409. The carriage members 406 and 408 are provided with guide holes adapted to slide along rods 410 and 412 extending between the side frame members of the machine. In like manner, support members 178 and tractor drive wheels 172 are keyed to slide along square shaft 170. In order to effectuate the lateral adjustment, an adjustment knob 414 is provided on a threaded shaft 416 extending through and engaged with a threaded opening 418 through carriage member 406. It is to be understood that the threads on threaded shaft 416 are of opposite hand at opposite ends of the shaft so that the carriage member 406 on one side will be moved in one direction and the carriage member 406 on the other side will be moved in the opposite direction upon rotation of threaded shaft 416 by operation of adjustment knob 414. In this way, the side die means 180 and intermittent feed means 120 on one side of the machine and the side die means 180 and intermittent feed means 120 on the other side of the machine can be driven together or apart by rotation of adjustment knob 414 in one direction or the other.

A generally similar arrangement is provided for the adjustment of the pair of heater means and side flap fold means. Each of carriages 330 for the side fold mechanism 328 is provided with a pair of slide members 420 and 422 secured on the bottom side thereof by means of screws 424. Slide 420 has a hole adapted to receive a guide rod 426 extending between the side frame members of the machine, and slide 422 likewise has a hole adapted to receive a guide rod 428 extending between the side frame members of the machine. A bracket 430 is secured to carriage 330 by means of screws 432 and extends downwardly and rearwardly supporting a heater mounting plate 434 at its lower end. Guide holes 436 and 437 in bracket 430 and plate 434 are received on a guide rod 438 extending between the side frame members of the machine. It will be observed that heater 374 and pressure plate assembly 376 are mounted on mounting plate 434. The lateral adjustment of the side fold and heater means on opposite sides of the machine is effectuated by means of an adjustment knob 440 mounted on a threaded shaft 442 extending between the side frame members of the machine and threadedly engaged with threaded holes 444 provided in depending carriage members 446

secured to the bottoms of carriages 330 by suitable screws. Shaft 442 is provided with threads of opposite hand at opposite ends of the shaft so that the carriages 446 at opposite sides of the machine will be driven in opposite directions upon rotation of threaded shaft 442 in a given direction. Thus, the side fold means and heater means on one side of the machine and the side fold and heater means on the other side of the machine may be adjusted to move toward each other or apart from each other when adjustment knob 440 is rotated in one direction or the other.

The method and operation of the apparatus of the invention will be best understood by first considering the manner in which a continuous envelope form 26 of the invention is engaged with the intermittent feed means 120 of envelope converter 110. Turning to FIGS. 7 and 8, it will be noted that feed pins 124 extend through a slot 450 in a metal indicia plate 452. A plurality of indicia 454, 456, and 458, being the indicia B, G, R, respectively, are inscribed adjacent suitable index lines on one of the plates 452 at different positions along slot 450. In addition, a transverse form support plate 460 is provided on the input end of the machine, this plate being inscribed with a pair of guide marks 462 adjacent opposite side edges of the form as it is fed into the machine.

It will be observed from FIG. 7 that a safety cover plate 464 is hinged on support member 178 and is provided with a slot 466 which will be aligned with slot 450 when cover plate 464 is closed. A pair of springs 468 and 470 serve normally to bias cover plate 464 in its closed position. The cover plate 464 will serve to maintain the continuous envelope form in engagement with feed pins 124 and will, in the normal operation of the machine, be in the closed position. However, when a new envelope form is to be engaged with the feed pins 124, cover plate 464 will be pivoted to its open position as seen in FIG. 7. It is also to be observed from FIG. 4 that a hand wheel 472 is mounted on drive shaft 135 making it possible to manually drive the drive means of the envelope converter.

When a new continuous envelope form 26 is to be inserted into envelope converter 110, the safety cover plates 464 are raised to the open position shown in FIG. 7 thereby exposing indicia plate 452. The raising of safety cover plate 464 also serves to open a micro-switch (not shown) de-energizing the electric circuit of motor 126 which will thus now be inoperative. An addressed zig-zag folded stack 28 will now be placed on table 112 at the input side of converter 110. It is to be noted that continuous envelope form 26 is a pin folded that the form will be fed into envelope converter 110 with the side of the form having the adhesive coatings 76, 78 and 80 facing upwardly and with the printed and addressed side of the form facing downwardly. Before feeding the form into the machine, the operator should take note of the index indicia 70, 72, or 74 appearing on the leading full envelope blank section 46. He will then turn the hand feed wheel 472 until the intermittent feed means 120 enters a dwell period. Index indicia 454, 456 and 458 are so positioned that one of them will be in alignment with a feed pin when this occurs. The operator should check to see which of the index indicia 454, 456 and 458 is in alignment with a pin 124. If the indicia does not correspond with the indicia on the lead-

ing full envelope blank section 46, the hand wheel should again be advanced until the index indicia 456, 458 or 460 corresponding to the index indicia 70, 72 or 74 on the leading full envelope blank section is in alignment with a feed pin and the intermittent feed means 120 is in a dwell period. Thus, if the operator were feeding the continuous envelope form 26 shown in FIG. 2, he would note that indicia G appears on the leading full envelope blank section 46. He will thus continue to advance hand wheel 472 until the corresponding indicia G is brought into alignment with a pin 124 during a dwell period of feed means 120, this being the condition shown in FIG. 8. The operator will now be ready to engage continuous envelope form 26 with feed pins 124. However, he should first check to determine whether the envelope form fits between the pins on each side of the machine without a buckle. If it does not, adjustment of the spacing between the pin feed means may be effected by adjustment of knob 414. With the continuous envelope form 26 engaged with the feed pins 124, handwheel 472 will be advanced to feed the envelope form slowly into the converter until the first fold line 48 of the first full envelope blank section 46 is brought into alignment with guide marks 462. If this correspondence between first fold line 48 and guide marks 462 cannot be made, the envelope form 26 should be advanced one or more pins until correspondence between the first fold line 48 and guide marks 462 is achieved. The safety cover plates 464 will now be closed, and hand wheel 472 will be turned to advance the envelope form forward. At the same time, the operator will actuate a scrap latch control lever 474 (see FIG. 4) to turn shaft 476 extending between side frame members 276 and 284 to rotate the scrap blocking structure 304 to the position shown in dash line in FIG. 6. When blocking structure 304 is so pivoted, it will block the path from cutting knife 286 causing the leading end 84 of continuous envelope form 26 to engage against the lower surface 478 of blocking structure 304. As will be evident from FIG. 6, this lower surface 478 will be in alignment with a guide surface 480 provided by a suitable guide plate to divert the leading partial envelope blank section 82 downwardly into a waste receptacle 482. Scrap latch lever 474 will now be returned to its normal position, bringing blocking structure 304 back to its normal position shown in full lines in FIG. 6. The operator should then continue to advance hand wheel 472 until a completed envelope 114 is discharged from the machine. He should then check the completed envelope and, if the envelope is in satisfactory condition indicating that no adjustments of the machine are required, the operator may determine that the machine is now ready for a production run. This will be initiated by closing a starting switch for motor 126. The motor will then drive main drive pulley 128 and drive shaft 135. Since the machine was in a dwell period at the time of energization of motor 126, continuous envelope form 26 will be stationary and upper die members 182 and knife head assembly 264 will be in their lower positions. At this time, intermitting gear 148 will be disengaged from the teeth of intermitting drive gear 142 which is now being driven by belt 136 from pulley 132 on shaft 135. Shaft 140, in turn, is coupled through pulley 194 and belt 196 to drive cam 202 and through

pulley 250 and belt 252 to drive eccentric 258. Thus, as shaft 135 continues to rotate, cam 202 will cause upper die member 182 to reciprocate vertically upwardly and eccentric arm 260 will raise knife head assembly 264. 5 Intermitting gear 148 will then become engaged with the teeth of intermitting drive gear 142 to drive tractor drive wheel 172 causing the intermitting feed means to feed continuous envelope form 26 forwardly to bring a full envelope blank section 46 into the machine. This 10 forward feed of the envelope blank section will continue until intermitting gear 148 becomes disengaged from the teeth of intermitting drive gear 142 as the machine enters the next dwell period. The line of division 58 on envelope form 26 will now be directly below cutting knife 286. As shaft 135 continues to rotate, cam 202 will now drive upper die members 182 downwardly and eccentric 258 will drive knife head assembly 264 downwardly. Die punch 184 will be become engaged 15 with continuous envelope form 26 simultaneously with the engagement of cutting knife 286 with the line of division 58. Cutting knife 286 will thus sever the continuous envelope form along line of division 58 corresponding to the leading edge of the envelope blank section 46 just fed into the machine and corresponding to the trailing edge of the envelope blank section 46 leading and contiguous with the envelope blank section just fed into the machine. At the same time, die punches 184 will sever the side trim zones 66 and 68 20 longitudinally of the form along longitudinal score lines 30 and 32 between first fold line 48 and their respective intersection with diagonal slashes 62 and 64 and transversely along first fold line 48 between longitudinal score lines 30 and 32 and the respective side edges 34 and 36 of the form. Immediately after this action of the die punch 184 and cutting knife 286, scrap removing rod 226 will be rotated into engagement with the side trim zones positively to deflect them downwardly. 25

When envelope blank section 46 was fed into the machine, the leading edge of the leading contiguous envelope blank section 46 was fed through the gap between pinch roller 312 and drive rollers 306. When, however, knife head assembly 264 descended to engage cutting knife 286 with the form along the line of division 58, pinch rollers 312 became engaged with the upper side of the envelope form to drive the leading envelope blank section 46 forwardly immediately after it was severed from the form along its trailing edge. This 30 forward drive of the now severed envelope blank section will continue until its leading edge is engaged by drive rollers 332 and 334. These rollers will continue to drive the envelope blank section forwardly bringing side flaps 67 and 69 into engagement with the respective side flap fold means 328 causing the side flaps to be raised and folded over bottom sheet portion 50 of the envelope blank. The leading edge of the envelope blank will next be engaged by drive rollers 354 and 356 and be driven in guide chute 360. As the leading edge 35 of the envelope blank engages stop 366, first fold line will be positioned directly above the nip between roller 356 and 370. The engagement of the leading edge with stop 366 will cause buckling of the form along this fold line causing engagement of the form on opposite sides of first fold line 48 by rollers 356 and 370. This will cause the folded envelope blank to be driven along a downward path between respective heaters 374 and

pressure plates 376 overlying the side flaps folded over into engagement with the adhesive coating 78 and 80. The heat and pressure provided by heater 374 and pressure plate 376 will activate the adhesive coatings causing the side flaps to be adhesively secured to the top sheet portion of the envelope blank. The envelope blank will now pass between rollers 380 and 382. The pressure supplied by these rollers will complete the seal between side flaps 67 and 69 and top sheet portion 52. These rollers will also drive the envelope into guide chute 392. When the leading folded edge of the envelope engages stop 398, fold line 54 will be positioned immediately in front of the nip between rollers 380 and 400. Upon engagement with stop 398, the envelope will buckle along fold line 54 causing rollers 380 and 400 to engage the envelope on opposite sides of fold line 54 feeding the envelope in direction 402 and at the same time folding closure flap portion 56 over bottom sheet portion 50.

The completed envelopes will now be discharged in the direction of arrow 402. The completed envelopes 114 will fall to conveyor belt 116 and be assembled in a stack 118 at the output side of the machine. These envelopes will be in the form shown in FIGS. 3 and 3A. 25 Bottom sheet portion 50 is folded over top sheet portion 52 along fold line 48 and closure flap portion 56 is folded over bottom sheet portion 50 along fold line 54. The side flaps 67 and 69 are folded under bottom sheet portion 50 and are adhesively secured to top sheet portion 52 as is most clearly shown in FIG. 3A. Since the envelopes will be provided with the closure flap portion 56 folded over the bottom sheet portion, they will now be ready for use with conventional automatic inserting machinery. Since the envelope converter 110 is provided with means for adjusting the lateral spacing of intermittent feed means, side die means, side fold means, and heater means, envelopes of various widths may be provided: for example, in an existing physical embodiment of the invention, envelope sized Nos. 6 through 10 may be provided by a single machine.

While a preferred embodiment of the invention has been shown and described, it will be apparent to those skilled in the art that changes can be made without departing from the principles and spirit of the invention, the scope of which is defined in the appended claims.

The invention claimed is:

1. A continuous forms envelope converter for receiving a continuous paper strip having a pair of longitudinal lines of weakness spaced inwardly from the sides of said strip to provide side margins, a longitudinal row of pinfeed holes in each of said side margins, a plurality of successive integral envelope blank sections, each of said envelope blank sections being provided with a first transverse line of weakness extending from one side edge of said strip to the other side of the strip and constituting a first fold line between a bottom sheet portion and a top sheet portion of said envelope blank section, each of said envelope blank section being provided with a second transverse line of weakness extending from one of said longitudinal lines of weakness to the other of said longitudinal lines of weakness and constituting a second fold line between said top sheet portion and a closure flap portion of said envelope blank section, said closure flap portion having an edge corresponding to the leading edge of said envelope blank

section contiguous with the trailing edge of an adjacent envelope blank section, and adhesive coatings on said closure flap and adjacent to the side margins of said top sheet portion, said strip being fan folded to form a zig-zag folded stack, said converter comprising:

a pair of intermittent feed means for engaging respectively said row of pinfeed holes in each side margin for feeding said strip from said zig-zag folded stack;

a pair of die means for dieing out portions respectively of said side margins adjacent said top sheet portion and said closure flap portion, the portions of said side margins adjacent said bottom sheet portion then constituting side flaps integral with said bottom sheet portion;

means for separating said envelope blank sections from said strip at said trailing edge of said envelope blank sections;

a pair of side flap fold means for folding a respective side flap over said bottom sheet portion;

means for folding said top sheet portion over said bottom sheet portion along said first fold line to bring said folded over side flaps into engagement with the adhesive coatings on said top sheet portion;

a pair of heater means for activating respectively the adhesive coating on said top sheet portion;

means for folding said closure flap portion over said bottom sheet portion; and

adjustment means for adjusting the spacing between said pair of intermittent feed means, said pair of die means, said pair of side flap fold means, and said pair of heater means, whereby said converter may be adjusted to produce addressed envelopes of different lengths.

2. A continuous forms envelope converter as recited in claim 1, wherein said adjustment means comprises first means for simultaneously adjusting the spacing between said pair of intermittent feed means and said pair of die means and second means for simultaneously adjusting the spacing between said pair of side flap fold means and said pair of heater means.

3. A continuous forms envelope converter as recited in claim 1, wherein one of said intermittent feed means on one side is structurally tied to said die means on that side, the other of said pair of intermittent feed means on the other side is tied to said die means on the other side, bracket means joins one of said pair of heater means and one of said side fold means on the one side, and second bracket means joins the heater means and side flap fold means on the other side, said first means comprising a first screw member having an adjustment knob and being coupled to said die means on said one side and said die means on the other side so as to move said die means toward or away from each other and second means including a screw device having an adjusting knob engaged with said brackets on each side for moving said brackets toward or away from each other for simultaneously adjusting the spacing between said heater means and said side flap fold means.

4. A continuous forms envelope converter for receiving a continuous paper strip having a pair of longitudinal lines of weakness spaced inwardly from the sides of said strip to provide side margins, a longitudinal row of pinfeed holes in each of said side margins, a plurality

of successive integral envelope blank sections, each of said envelope blank sections being provided with a second transverse line of weakness extending from one of said longitudinal lines of weakness to the other of said longitudinal lines of weakness and constituting a second fold line between said top sheet portion and a closure flap portion of said envelope blank section, said closure flap portion having an edge corresponding to the leading edge of said envelope blank section contiguous with the trailing edge of an adjacent envelope blank section, and adhesive coatings on said closure flap and adjacent to the side margins of said top sheet portion, said strip being fan folded to form a zig-zag folded stack, said converter comprising:

intermittent feed means for engaging said rows of pinfeed holes for feeding said strip from said zig-zag folded stack;
 die means for dieing out portions of said side margins adjacent said top sheet portion and said closure flap portion, the portions of said side margins adjacent said bottom sheet portion then constituting side flaps integral with said bottom sheet portion;
 knife means for cutting said strip along said trailing edges of said envelope blank sections for separating said envelope blank sections from said strip;
 side flap fold means for folding said side flaps over said bottom sheet portion;
 means for folding said top sheet portion over said bottom sheet portion along said first fold line to bring said folded over side flap portions into engagement with said adhesive coatings on said top sheet portion;
 heater means for activating the adhesive coatings on said top sheet portion;
 means for folding said closure flap portion over said bottom sheet portion; and
 drive means coupled to said intermittent feed means, to said knife means, and to said die means, said drive means driving said knife means and said die means for simultaneous operation when said intermittent feed means is in a dwell period with said strip stationary beneath said knife means and die means.

5. A continuous forms envelope converter as recited in claim 4, wherein said intermittent drive means comprises a first gear driven by said drive means, a portion of the circumference of said first gear being provided with gear teeth and the remainder of the circumference of said first gear being free of gear teeth, a second gear adapted to be driven by said first gear when engaged with the teeth of said first gear and to remain stationary in a dwell period when the portion of the first gear having no teeth moves past said second gear, a pinfeed tractor assembly driven by said second gear and having a plurality of pins adapted to engage with said pinfeed holes to move said strip into said envelope converter when said second gear is engaged with the teeth of said first gear and to hold said strip in a dwell period when said second gear is disengaged from the teeth of said first gear.

6. A continuous forms envelope converter as recited in claim 5, wherein said first gear comprises a cam track and said second gear comprises a cam follower engageable with said cam track, said cam track being so positioned and shaped as to lift said gear teeth of

5 said second gear from said gear teeth of said first gear at a point on said first gear where said gear teeth discontinue and to engage said gear teeth of said second gear to the gear teeth of said first gear at a point where the gear teeth of said first gear begin.

7. A continuous forms envelope converter as recited in claim 4, wherein said knife means is mounted for vertical reciprocation into engagement with said continuous strip by means of an eccentric driven crank arm 10 coupled to said drive means and wherein said die means is driven for vertical reciprocation into engagement with said strip simultaneously with the engagement of said strip by said knife means by means of a cam coupled to said drive means through a timing belt.

15 8. A continuous forms envelope converter as recited in claim 7, further comprising finger means operated synchronously with said die means for downwardly deflecting the died out portions of said side margins to insure their separation from said strip.

20 9. A continuous forms envelope converter as recited in claim 7 further comprising envelope blank section feed means having a driven roller and a pinch roller, said pinch roller being reciprocated downwardly with said knife means to engage the envelope blank section immediately after it is separated from said strip by said knife means to feed it to said side fold means, said pinch roller being biased out of engagement from said drive roller when said knife means reciprocates upwardly.

25 10. A continuous forms envelope converter for receiving a continuous paper strip having a pair of longitudinal lines of weakness spaced inwardly from the sides of said strip to provide side margins, a longitudinal row of pinfeed holes in each of the said side margins, said pinfeed holes being spaced in accordance with the spacing of the pinfeed holes on conventional computer print-out paper, a plurality of successive integral envelope blank sections of such length along said strip as to conform, when converted into an envelope, to a conventional envelope width, said pinfeed holes on successive envelope blank sections being placed at different positions relative to the leading edge of the envelope blank section, said relative position of pinfeed holes to leading edge repeating every n envelope blank sections, where n is an integer greater than one, said strip having recurrent series of n envelope blank sections, each section of said series having pinfeed holes 30 with the same relative position to leading edge as corresponding sections in each of the series, indicia on each of said envelope blank sections signifying the relative position of pinfeed holes to leading edge on that section, each of said envelope blank sections being provided with a first transverse line of weakness extending from one side edge of said strip to the other side edge of the strip a constituting a first fold line between a bottom sheet portion and a top sheet portion of said blank section, and each of said envelope blank sections being 35 provided with a second transverse line of weakness extending from one of said longitudinal lines of weakness to the other of said longitudinal lines of weakness and constituting a second fold line between said top sheet portion and a closure flap portion of said envelope blank section, said closure flap portion having an edge corresponding to the leading edge of said envelope blank section contiguous with the trailing edge of an

40 45 50 55 60 65

adjacent envelope blank section, said strip being fan folded along said first fold line of each envelope blank portion to form a zig-zag folded stack, said converter comprising:

5 intermittent feed means including a plurality of successive feed pins for engaging said rows of pinfeed holes in said side margins for feeding said strip from said zig-zag folded stack;

die means for dieing out portions of said side margins adjacent said top sheet portion and said closure flap portion, the portions of said side margins adjacent said bottom sheet portion then constituting side flaps integral with said bottom sheet portions; means for separating said envelope blank sections 10 from said strip at said trailing edge of said envelope blank sections;

15 side flap fold means for folding said side flaps over said bottom sheet portion;

means for folding said top sheet portion over said 20 bottom sheet portion along said first fold line;

index means providing n index indicia adjacent said 25 intermittent feed means corresponding to the indicia on each of said envelope blank sections of said recurrent series and a first fold line index mark adjacent said intermittent feed means; and manual feed means for advancing said feed pins of said intermittent feed means to bring one of said feed pins into alignment with the index indicia of said index means corresponding to the indicia on the leading full envelope section of said strip, said index indicia being so positioned that the leading edge of said leading full envelope blank section will be properly positioned relative to said means 30 for separating said envelope blank sections when said feed pin and index indicia are so aligned and said first fold line of said leading full envelope blank section is aligned with said index mark.

11. A continuous forms envelope converter as recited in claim 10, wherein said spacing of said pinfeed holes is one-half inch, center-to-center, said length of said envelope blank section is $9\frac{1}{8}$ inches, and n is equal to 3.

12. A continuous forms envelope converter for receiving a continuous paper strip having a pair of longitudinal lines of weakness spaced inwardly from the sides of said strip to provide side margins, a longitudinal row of pinfeed holes in each of said side margins, a plurality of successive integral full envelope blank sections, a first transverse line of weakness on each of said envelope blank sections extending from one side edge of the strip to the other side edge of the strip and constituting a first fold line between a bottom sheet portion and a top sheet portion of said envelope blank section, a second transverse line of weakness on each of said envelope blank sections extending from one of said longitudinal lines of weakness to the other of said longitudinal lines of weakness and constituting a second fold line between said top sheet portion and a closure flap portion of said envelope blank section, said closure flap portion having an edge corresponding to the leading edge of said envelope blank section contiguous with the trailing edge of an adjacent envelope blank section, the leading full envelope blank section having a leading edge contiguous with the trailing edge of a leading partial envelope blank section, said leading

partial envelope blank section having a dimension longitudinally of the strip equal to the distance between the trailing edge of a full envelope blank section and said first fold line, said continuous strip being fan folded along said first fold line to form a zig-zag folded stack, said envelope converter comprising:

intermittent feed means for engaging said rows of pinfeed holes in each side margin for feeding said strip from said zig-zag folded stack;

die means for dieing out portions of said side margins adjacent said top sheet portion and said closure flap portion, the portions of said side margins adjacent said bottom sheet portion then constituting side flaps integral with said bottom sheet portion;

means for separating said envelope blank sections from said strip at said trailing edge of said envelope blank sections;

side flap fold means for folding said side flaps over said bottom sheet portion;

means for folding said top sheet portion over said bottom sheet portion along said first fold line;

means for adhesively securing said folded over side flaps to said top sheet portion;

manual feed means for manually advancing said intermittent feed means to feed the leading edge of said strip into said envelope converter after engagement of said pinfeed holes with said intermittent feed means; and

blocking means for diverting said leading partial envelope blank section to a waste receptacle after it is separated from said strip by said means for separating said envelope blank sections from said strip.

13. A continuous forms envelope converter as recited in claim 12, wherein said blocking means comprises a member pivotable to a first position blocking movement of said envelope blank sections to said side fold means and pivotable to a second position permitting movement of said envelope blank sections to said side fold means.

14. A continuous forms envelope converter for receiving a continuous paper strip having a pair of longitudinal lines of weakness spaced inwardly from the sides of said strip to provide side margins, a longitudinal row of pinfeed holes in each of said side margins, a plurality of successive integral envelope blank sections, each of said envelope blank sections being provided with a first transverse line of weakness extending from one side edge of said strip to the other side of the strip and constituting a first fold line between a bottom sheet portion and a top sheet portion of said envelope blank section, each of said envelope blank sections being provided with a second transverse line of weakness extending from one of said longitudinal lines of weakness to the other of said longitudinal lines of weakness and constituting a second fold line between said top sheet portion and a closure flap portion of said envelope blank section, said closure flap portion having an edge corresponding to the leading edge of said envelope blank section contiguous with the trailing edge of an adjacent envelope blank section, and adhesive coatings on said closure flap and adjacent to the side margins of said top sheet portion, said strip being fan folded to form a zig-zag folded stack, said converter comprising:

a pair of intermittent feed means for engaging respectively said row of pinfeed holes in each side margin for feeding said strip from said zig-zag folded stack; a pair of die means for dieing out portions respectively of said side margins adjacent 5 said top sheet portion and said closure flap portion, the portions of said side margins adjacent said bottom sheet portion then constituting side flaps integral with said bottom sheet portion;
 means for separating said envelope blank sections 10 from said strip at said trailing edge of said envelope blank sections;
 a pair of side flap fold means for folding a respective side flap over said bottom sheet portion;
 first fold means for folding said top sheet portion 15 over said bottom sheet portion along said first fold line to bring said folded over side flaps into engagement with the adhesive coatings on said top sheet portion, said first fold means including first guide means for receiving each of said envelope blank sections, means for conveying said blank sections into said guide means, leading edge first, first stop means on said first guide means for engaging said leading edge to cause said envelope blank sections to buckle along said first fold line, 25 and first roller means for engaging said blank sec-

tions on opposite sides of said fold line for engaging said bottom sheet portion with said top sheet portion and for conveying said folded envelope blank sections in a downward path, folded edge first;
 a pair of heater means along said downward path for activating respectively the adhesive coatings on said top sheet portion to form completed envelopes; and
 second fold means for folding said closure flap portion over said bottom sheet portion, said second fold means including second guide means below said pair of heater means for receiving each of said completed envelopes conveyed along said downward path, folded edge first, from said pair of heater means, second stop means on said second guide means for engaging said folded edge to cause said completed envelopes to buckle along said second fold line, and second roller means for engaging said completed envelopes on opposite sides of said second fold line for engaging said closure flap portion with said bottom sheet portion and for conveying said completed envelopes along a horizontal path to discharge said completed envelopes from said converter.
